UNITED STATES PATENT OFFICE.

HOOPER COYNE, OF BALTIMORE, MARYLAND.

SAFETY-RAZOR.

1,094,127.

Specification of Letters Patent. Patented Apr. 21, 1914.

Application filed May 17, 1913. Serial No. 768,294.

To all whom it may concern:

Be it known that I, HOOPER COYNE, a citizen of the United States, residing at Baltimore, in the State of Maryland, have invented certain new and useful Improvements in Safety-Razors; and I do hereby declare the following to be a full, clear, and exact description of the invention, such as will enable others skilled in the art to which it applies to make and use the same.

My invention relates to improvements in safety razors, and it consists in the constructions herein described and claimed.

An object of my invention is to provide an improved safety razor adapted to shave smoothly and easily without danger of cutting or injury to the face, and provided with means for preventing the retention and accumulation of the soap and other matters at the cutting edge of the razor.

A further object of my invention is to provide a simple and efficient safety razor consisting of a guard and a double-edged blade adapted to be clamped in position thereon with either side against said guard and either end forward.

In the accompanying drawings, forming a part of this application and in which similar reference symbols indicate corresponding parts in the several views:—Figure 1 is a side view of a razor illustrating one embodiment of my invention; Fig. 2 is a side view of my improved razor blade; Fig. 3 is an end view of the blade; Fig. 4 is an edge view of the guard and its attachment to the razor handle; Fig. 5 is an enlarged section on the line 5—5 of Fig. 1; Fig. 6 is an enlarged fragmentary perspective view of one of the wedge-shaped clamping members stamped upwardly from the metal guard; and Fig. 7 is a face view, showing my invention applied to a corn knife.

Referring to the drawings, 1 indicates a guard comprising a flat metal strip formed symmetrically to a longitudinal axis passing through its pivotal connection 2 to the spaced handle members 3, whereby said guard and its attached blade can be swung into closed, or protected, position within said handle from either side of the latter.

The flat strip 1 is provided with a pair of integral medially-extending trapezoidal clamping members 4 formed by cutting converging incisions through said strip to form the inclined side edges 5 of said members, and then stamping upwardly the portion of

said strip between said converging incisions to space said members above the upper face of the strip by upstanding end webs 6 extending along the respective ends of said members; the ends of said upstanding webs being notched or cut away to provide overhanging clamping portions along the inclined edges 5 of said members 4. The flat strip 1 is shown provided with longitudinally-extending series of apertures 7 spaced from its side edges and having outer walls 8 inclined inwardly from the front face of said strip.

A flat razor blade 9 is provided with a pair of opposite V-shaped cutting edges adapted to lie slightly within the inwardly inclined outer faces 8 of the apertures 7, whereby said inwardly-inclined faces act to direct the lather and other matter inwardly beneath the lower bevel of said V-shaped cutting edge for preventing the troublesome accumulation of such matter on the guard strip adjacent to the cutting edge of the blade.

The flat razor blade 9 is provided with slots 10 arranged symmetrically to the longitudinal and transverse axes of said blade; each of said slots being formed by a pair of duplicate trapezoidal openings extending symmetrically from a common base. This provides an improved and simple construction by which said slots 10 are adapted to receive the trapezoidal members 4 and permit the razor blade to be slipped beneath the free overhanging portions of said trapezoidal members with either end of the blade toward the outer end of the guard strip 1; thereby enabling the blade to be clamped in position with either cutting edge in cutting relation to the desired edge of said guard strip 1. When the razor blade 9 is thus slipped beneath the overhanging edges 5 of the trapezoidal members 4, the edges of the relatively thin end webs 6 of each of said members are wedgily gripped at points spaced along the inclined edges of the corresponding blade slot 10; thereby giving a strong gripping pressure localized at spaced points along each slot 10 for firmly clamping the blade in position.

Fig. 7 illustrates my invention applied to a corn knife, or similar implement provided with a rounded handle 11 rigidly secured to the shank of the guard strip 1.

From the above description it will be clear that my invention provides an im-

proved safety razor, in which the blade can be readily clamped in an effective shaving position with either face against the guard strip and with either end forward.

5 I have illustrated and described preferred and satisfactory constructions, but changes could be made within the spirit and scope of my invention.

I claim:

- 10 A safety razor comprising a flat guard plate having a pair of medially-extending flat trapezoidal clamping members supported above its upper face by integral spaced end webs terminating slightly within the inclined edges of said trapezoidal members, and a flat razor blade having cutting edges on its opposite sides and provided
- 15

with medially-extending slots arranged symmetrically to the transverse axis of said blade, each of said slots being formed by a 20 pair of duplicate trapezoidal openings extending symmetrically from a common base for receiving said trapezoidal members for clamping said blade on said guard, whereby the razor blade may be attached to said 25 guard in reverse directions, substantially as described.

In testimony whereof, I affix my signature, in presence of two witnesses.

HOOPER COYNE.
